2 SHEETS-SHEET 2.

UNITED STATES PATENT OFFICE.

BERNHARD BESKOW, OF SAN FRANCISCO, CALIFORNIA.

SPEED-CHANGING MECHANISM.

No. 905,637.

Specification of Letters Patent.

Patented Dec. 1, 1908.

Application filed April 5, 1906. Serial No. 310,112.

To all whom it may concern:

Be it known that I, BERNHARD BESKOW, citizen of the United States, residing at San Francisco, in the county of San Francisco and State of California, have invented certain new and useful Improvements in Speed-Changing Mechanism, of which the following is a specification.

My invention relates to controlling devices 10 for speed changing mechanism for automobiles and the like.

One object of the invention is to provide means by which the flywheel clutch used in connection with the sliding gear transmission can be automatically released and as 15 gradually as desired engaged when changing from one rate of speed to another. When releasing the clutch, the motor is also automatically throttled down, so all racing of 20 the motor, when under no load, is entirely avoided. This automatic device for releasing the clutch will guard against the stripping of gears, when the car is operated by an inexperienced driver, who may not remember 25 the rule, that whether on the level, up hill, or reversing, the clutches should always be entirely disengaged before attempting a change of speed.

Another object is to provide 30 means for automatically applying the brake before changing from slow speed forward to reverse, or vice versa.

A further object is to provide an automatical device for keeping all gears out of 35 mesh, when driving at the highest speed. When drawn into contact again in changing from high speed to intermediate, the gears are dead at first and consequently can be shifted without any severe strain on the gear 40 teeth.

The different operations are all performed through one lever, thus dispensing with one foot pedal and one or more side levers, the advantages of which are obvious. The 45 lever, in my construction, when drawn back as far as it will go, will cause the motor to run the machine backwards, but when it is pushed forward beyond a certain limit it will cause the motor to run the machine forward 50 at the slowest rate of speed and, thereafter as its position is forwardly changed, it will bring about an increase in the rate of speed at which the machine will be moved until the highest rate of speed is reached, and in 55 every case proper movements of the clutch, throttle and brake will be automatically at-

tended to. The mechanism for accomplishing this is very simple and is embodied in the accompanying drawings in which:

Figure 1 is a top plan view of the gear case 60 partially broken away, showing the main and countershaft and gears in connections therewith and operated by the controlling shaft, and the levers actuated by said shafts. Fig. 2 is a broken end view of the gear case, lying 65 on one of its sides. Fig. 3 is a side elevation in natural position. Fig. 4 to Fig. 11 inclusive are diagrammatic illustrations of the different positions of the controlling lever, and the controlling shaft and the levers actuated thereby. The operating lever being 70 on the right side of Figs. 4 to 10 and on the left side of Figs. 5 to 11. Fig. 12 is a side elevation of the rack. Fig. 13 is a top plan view of the same. Fig. 14 is a side elevation 75 of one of the pinions, which engages with the rack.

Referring to the drawings 1 indicates the driven shaft and 1' the driving shaft; 2 the countershaft, and 3 the casing in which 80 said shafts are mounted in the ordinary manner.

One end of the driven shaft is provided with a universal joint 4, which is connected with the driving axle, not shown, in the 85 ordinary manner. The driven shaft 1 is connected with the driving shaft 1' within the casing by a male and female joint 5. Outside of the casing and opposite the universal joint the shaft 1' carries a clutch 90 member 6 of any approved type, which is rigidly connected therewith, the one shown in the drawings being provided with two yielding arms, to the free ends of which, dogs or levers 7 are pivotally secured. The 95 free ends of the levers 7 are moved outward by the insertion of the inclined face 8 of an annular jaw or wedge member 9, which is loosely mounted on the hub 10 of the clutch member 6, and which thereby gradually expands and forces the face of the yielding arms or cams against the inside rim of the flywheel 11, which is rigidly connected with the axle 12 of any suitable motor, not shown. 100

The wedge member 9 is normally held 105 separate from the free ends of the dogs 7 by a spring 13.

Within the casing 3 and fixed to the free end of the shaft 1' and rigidly connected with the female part of the joint 5 is a pinion 14. Slidably mounted upon shaft 1, 110 which is preferably angular in cross section,

are two spur gears, 15 and 16, and directly connected with each of said gears are sleeves 17 and 18, provided with annular grooves 19 and 20 respectively, the sleeve 17 being integral with the male part of joint 5. Rigidly connected with the countershaft 2 are pinions 21, 22 and 23 and slidably mounted upon it is a spur gear 24, provided with a sleeve 25, the latter having an annular groove 26. 10 Suspended underneath the pinion 21 and engaging therewith, is an idle pinion 27, by means of which the spur gear 16 is caused to rotate in the opposite direction from the shaft 1', as shown in Fig. 11, thereby causing the direction of the driving mechanism to be reversed.

Mounted upon suitable bearings on the casing 3 is a shaft 28, one end of which is preferably enlarged or provided with a hub 20 in which are formed cam grooves or tracks 29, 30 and 31 and at the other end it is provided with a segmental pinion 32. Loosely mounted upon the intermediate portion of the shaft is a sleeve 33, one end of which is provided 25 with cam grooves or tracks 34 and 35, and the other end is formed into or provided with a segmental pinion 36, which is similar and adjacent to the pinion 32.

Vertically mounted in suitable bearings on 30 opposite sides of the casing 3, are two rock shafts 37 and 38, each of which is provided at its upper end with an arm 39, which carries at its free end a roller 40, which rollers engage respectively with the cam 35 grooves 29, and 34. Secured to the portions of the shafts within the casing are two yokes, preferably formed with upper and lower arms 41 and 42 respectively, which arms are provided with projections 43 that fit in the 40 annular grooves 19 and 20, of the sleeves 17 and 18.

Pivoted on a support 44 in the bottom of the casing 3 is a lever 45, one arm of which is provided with a projection 46, that fits in the annular groove of the sleeve 25. The other arm is adapted to be engaged by a projection 47 carried on the lower arm of the yoke, that is fixed to the rock shaft 37. The parts are so arranged, preferably by 45 pivoting the lever nearer to the sleeve than to the projection, as to cause the joint to be opened before the gear 24 engages with the pinion 14. A spring 48 presses against the lever 45 and thereby normally holds the pinion 24 in engagement with the pinion 14.

Pivoted on top of the casing 3 are levers 49 and 50, the one end of each of which extends toward the shaft 28 and is provided with a roller 51, said rollers engaging respectively with grooves 30 and 31 on the enlarged part of shaft 28. Another lever 60 52 is also pivotally mounted on top of the casing, and the end that extends toward the shaft 28, is provided with a roller 53, which 65 roller engages with groove 35 in sleeve 33.

Supported in suitable bearings 54 and 55 on the side of the casing 3, is a rod 56 which, at one end is loosely connected with the outer end of lever 49, which is preferably provided with a crank bend. A projection or feather 70 57 on rod 56 travels in a corresponding slot in the bearings 55 and keeps the rod 56 from turning. Another rod 58 supported in a bearing 59 is provided at one end with a crossbar 60, which engages loosely with one 75 end of rod 56 and also with the free end of lever 52, said free end being also preferably provided with a crank bend. The other end of rod 58 is connected with a lever 61, which is pivoted at 62 and provided at its free end 80 with a projection 63, that fits in a groove formed in the periphery of the annular jaw or wedge member 9.

Pivoted on lever 61 at a point 64, is a rod 65 which is connected with the throttle of the 85 motor, not shown, in any suitable manner. The outer end of lever 50 is connected with a suitable brake 67 by means of rod 66, which is preferably divided, and the parts are held together by a tension spring 68. On top of 90 the casing 3 is further secured a guide 69, on which slides a rack 70, see Fig. 13, consisting of two portions 71 and 72, the teeth of which engage with the pinions 32 or 36 as the case may be, while the remaining portion is flat or 95 smooth for engaging with a flat face 73 formed upon each of said pinions. The two portions of the rack are arranged side by side and reversely to each other, and the teeth of each portion is a trifle less than half the 100 length of the rack, thereby leaving a smooth space at the center of the rack.

The pinions are of such size that the teeth formed upon a portion of the periphery of each will substantially equal the number of 105 teeth on its portion, whereby each pinion will be given only a partial revolution by the movement of the rack 70 a certain distance, for each pinion is so arranged relative to its segment, that the last tooth of the segment 110 engages with the last tooth of the pinion, and the further movement of the rack in that direction will cause the flat or smooth portion 74 to engage with the flat face 73 of the pinion, and thereby permit of the movement of 115 the rack without further rotation of the pinion. When the rack is moved in the opposite direction, said pinion will remain stationary until its teeth are engaged by the toothed portion of the rack, which will cause 120 its rotation until the opposite end of the rack is reached, when the pinion will have rotated as far as it can go and its flat face 73 will have been brought into engagement with the flat face 75 of a projection 76 at the end of the 125 rack.

By arranging the two segments opposite to each other as heretofore described, and arranging the two pinions to correspond therewith, it is evident, that when one of the pin- 130

ions is being actuated by the teeth of its portion the other pinion will be locked against rotation by its flat portion being engaged at the flat portion of the rack. For a very short 5 distance at the center of the rack, both pinions will be locked against rotation and their flat portions will slide upon the rack. The rack 70 may be moved back and forth on the guide 69 in any suitable manner; but I have 10 shown it as being connected with an ordinary lever 77, by means of rods or links 78 and 79 and bell crank 80. The lever 77 is provided with the ordinary detent 81, which is adapted to engage with a toothed quadrant 82 in 15 the usual manner, there being as many notches as there are changes of speed, and if desired an additional notch for the neutral point between reverse and slow. The lever is located at any convenient point of the 20 hicle, preferably adjacent to the side of the seat for the engineer or chauffeur.

From the foregoing description it will be seen that when the rack is moved in either direction by means of the operating lever, the 25 pinions and cam grooves operated thereby will be rotated in one direction or the other according as the lever is moved forward or back. In the drawings Fig. 1 and Fig. 4 the parts are shown in the position they occupy, 30 when the lever is set to drive the machine forward at its highest rate of speed. In this position motion is transmitted from the shaft 12 of the motor through the flywheel 11, clutch member 6, shaft 1', and male and female joint 5 to shaft 1 and through the universal joint 4 to the driving axle in the usual manner, which will drive the machine forward at the highest rate of speed.

By moving the lever 77 backward from 40 said position to the position shown in Fig. 5, the rack 70 will be also pulled backward, and the toothed portion 72 thereof, which is in engagement with pinion 36, will cause a partial rotation of said pinion and of sleeve 33 45 in the direction of the arrow. This movement of the sleeve is transmitted through groove 34, arm 39, and rockshaft 37, to the arms 41 and 42 on said shaft thereby separating the male from the female part of joint 50 5. At the same time the groove 35 will have caused the lever 52 to take the position shown in said figure. The cross bar 60 on rod 58 will be compelled to follow the motion of lever 52 by the spring 13 inside the flywheel, which is pushing the wedge member 9 out of contact with the free ends of dogs 7 55 and thereby releasing the friction clutch 6. The motor being thus free would race, but at the instant the wedge member 9 is pushed 60 out by means of the spring 13 the projection 63 fitting in the groove on the periphery of said wedge member forces the lever 61 backwards and with it the rod 65, which being in connection with the throttle, closes said 65 throttle to a degree previously determined

and thus reduces the speed of the motor. The gears being out of mesh, or in their neutral position, countershaft 2 is dead or non-rotating, and the shaft 1' that carries pinion 14 being also free, no power is transmitted 70 thereto, either direct from the motor or indirect from the momentum of the machine, and, therefore, the gear 24 can be thrown into mesh with pinion 14 by the lever 45 without danger of breaking the teeth of 75 either.

By pulling lever 77 further backward to position shown in Fig. 6, the following actions are executed through the motion of rack 70, pinion 36 and sleeve 33. The roller 80 53 on lever 52, following in the groove 35, brings the outer end of lever 52 back into the previous position and with it the rod 58. The lever 61, which is connected with rod 58, is consequently pulled over, which will cause 85 the lever 65 to reopen the throttle and thereby increase the speed of the motor. The projection 63 of arm 61, fitting in the groove on sleeve 9, forces said sleeve forward and causes the inclined face 8 to raise the face 90 ends of the dogs 7, thus gradually increasing the friction between the clutch and the flywheel. At the same time lever 39 causes such a movement of rockshaft 37 as to slide the sleeve 17, and with it gear 15, towards 95 pinion 23 and into mesh therewith. When the clutch has been expanded so as to be able to transmit power from the motor, the teeth of pinion 23 and gear 15 are in full mesh, as shown in said Fig. 6, without there having 100 been any danger of ripping the teeth. During this movement and at all other times except when the elements are standing in the position shown in Figs. 1 and 4, the gear 24 is held in mesh with pinion 14 by means of 105 the spring 48. By moving the lever 77 to the position shown in Fig. 7, the relative position of the controlling shaft, gears and levers will be neutral or identical with the position of same members in Fig. 5. The pinion 36 has now completed its revolution in the direction of the arrow and its flat face 73 is engaging with the flat portion 74 of the portion 72 of the rack. The flat surface of pinion 32 having at the same time reached 110 the limit of the smooth portion 74, its teeth are ready to engage with the teeth of the portion 71 and any further movement of the lever 77 backwards will cause the shaft 28 and the enlarged part thereof to revolve with 115 the pinion 32 in the direction of the arrow. The roller at the end of the lever 39, engaging with the groove 29, will thus be moved from its neutral position at the intermediate portion of said groove, as shown in Fig. 7, to the 120 end of the groove, as shown in Fig. 8, which will carry the opposite end of the lever 39 as far as it can go in that direction. This will cause such a rotation of the rock shaft 38 as to cause its arms 41 and 42 to slide the spur 125 130

gear 16 into mesh with pinion 22, as shown in said Fig. 8. At the same time that lever 39 is moved, lever 49 will be actuated by groove 30 and by means of the rod 56 will 5 pull the crossbar 60 backwards and with it rod 58, which, in its turn will, by means of lever 61, wedge member 9 and dogs 7, engage the fly wheel clutch 6 and transmit power to the driving axle as heretofore described, 10 thereby moving the machine forward at its slowest rate of speed.

By moving the lever 77 further backward or to a perpendicular position as shown in Fig. 9, the neutral position is again reached 15 and the position of the various members are identical with the position of same members in Fig. 7, except for groove 29, which has been given a half rotation.

If it should be desirable to reverse the direction of the machine from running forward at a slow rate of speed it is absolutely necessary to bring the machine to a stop before attempting to change the gears, the neglect of which would cause the ripping of the teeth. For 20 this purpose the groove 31 is so shaped that no motion is transmitted to lever 50, until at the proper moment between neutral and reverse, when the roller 51 on lever 50 strikes a tooth or projection in groove 31 which swings lever 50 into the position shown in Fig. 10 and causes it through rod 66 and spring 68 to 25 actuate the brake 67.

If for any reason the brake should be brought into action before the roller had 30 reached the top of the tooth, the spring 68 will allow the further movement of the roller until it has passed the top of the tooth. As the action of the tooth is very sudden there will be only a slight change in the relative 35 positions of the members that are actuated by the grooves 29 and 30, but when the roller has descended to the straight path of the groove 31 and the brake has been released, the roller on the arm 39 will have been carried to the other end of the groove 29, as 40 shown in Fig. 11, and thus caused the arm 41 to slide the gear 16 into full mesh with the pinion 27, which, being actuated by pinion 21, will bring about a reverse motion of the 45 driving axle through the universal joint 5, and drive the machine backward; the fly wheel clutch having been engaged through the movement of lever 49, rods 56 and 58 and lever 61 and the throttle opened by means of 50 rod 65.

In the construction as shown and above 55 described, the changes of speed are limited to four but it is obvious that the number thereof depends only upon the number of pinions and gears that may conveniently be placed 60 within the gear case, which gears in turn would call for a corresponding number of grooves and levers and pinions on the controlling shaft. And further it may be also 65 mentioned that if it should be desired to re-

duce the inertia of the main shaft when changing from intermediate to low speed, it can be accomplished in identically the same manner as is done in changing from high to intermediate. It would only be necessary to 70 connect the universal joint with the main shaft by means of a clutch of the type used for the flywheel or by a male and female joint, one part of which would be slidable on the main shaft like the joint for the high 75 speed gear. The mechanism for shifting the clutch or joint would be identical with the mechanism for operating the present flywheel clutch. Then, simultaneously with the release or engagement of the flywheel 80 clutch the universal joint would also be released or engaged and in the moment of changing from one rate of speed to another, no motion would be transmitted to any gears either indirect by the momentum of the machine, or direct by the motor, until the respective gears are in perfect mesh, when the power can be applied as gradually as desired. The same operating lever would take care of 85 all the different operations without the attention of the driver.

Although I have shown my improved controlling mechanism in connection with a sliding gear transmission, the device is just as well fitted for operating a planetary system 90 of transmission, or any other system, and I reserve the right to make all such changes as will come within the scope of my invention.

What I claim is:

1. In a controller for speed changing devices, a driving shaft, a driven shaft a separable joint for connecting said shafts, a counter-shaft, sets of gear wheels on said shafts, one of the wheels of one of said sets being on the driving shaft and the other one 100 on the counter-shaft, a lever for moving part of said wheels including said one on the counter-shaft, to change the speed of the driven shaft, a motor shaft, and means connected with the lever for disconnecting the 105 driving shaft from the motor shaft and opening said joint during the movement of the wheels to change the speed of the driven shaft.

2. In a controller for speed changing devices, a driving shaft, a driven shaft a separable joint connecting the driving shaft to the driven shaft a clutch at the end of the driving shaft, a counter-shaft, gear wheels on said shafts, a motor shaft a plurality of levers for 110 moving said wheels to change the speed of the driven shaft and controlling the joint, the clutch and the motor shaft during said change, a rod for connecting two of said levers, means for moving all of said levers, 115 and a lever for controlling said means.

3. In a controller for speed changing devices, a driving shaft, a driven shaft a separable joint connecting the shafts together, a clutch on the driving shaft, a counter-shaft' 120

gear wheels on said shafts, a motor shaft with which the clutch engages, a plurality of levers for moving said wheels to change the speed of the driven shaft, and also for controlling the 5 joint, the clutch and the motor shaft during said change, two of said levers being connected, a member provided with two cam grooves, one of which controls the shifting of the wheels and the opening and closing of 10 the joint and the other one controls the motor shaft and the clutch, and a lever for moving said member.

4. In a controller for speed changing devices, a driven shaft, gear wheels for changing 15 the speed of the driven shaft, a plurality of levers for moving the wheels including an engine controlling lever, two members, each provided with two cam grooves, one of the grooves of each member controlling the 20 wheel shifting levers and the other groove controlling the engine controlling lever, means for moving said members and locking one while the other one is being moved, and a lever for controlling said means.

25 5. In a controller for speed changing devices, a driven shaft, gear wheels for changing the speed of the said shaft, a plurality of levers for controlling said wheels including the motor controlling lever, two of which are 30 provided with extensions, two rods for loosely connecting said extensions with the motor controlling lever, means for moving said levers and a lever for controlling said means.

6. In a controller for speed changing devices, speed changing mechanism, levers for controlling the speed changing mechanism including a motor controlling lever, two rods, one of which is connected with the motor controlling lever and provided with a cross 40 head, and the other one has each end bent at an angle, one of which ends is adapted to be engaged by the cross head and the other end is adapted to be engaged by one of the other levers, another of said levers being 45 adapted to engage the cross head, means for controlling the movement of said levers, and a lever for controlling said means.

7. In a controller for speed changing devices, speed changing mechanism, a plurality 50 of levers for controlling said mechanism a motor controlling lever, brake mechanism, a plurality of rotatable, grooved members for controlling said levers, one of the grooves of one of said members being adapted to actuate the brake mechanism, means for rotating said members, and a lever for actuating said means, whereby the brake is automatically applied when the speed is changed from slow to reverse. 55

In testimony whereof I have affixed my signature, in presence of two witnesses, this 28th day of February 1906.

BERNHARD BESKOW.
